UNITED STATES PATENT OFFICE.

JOHN NAZEL, OF PHILADELPHIA, PENNSYLVANIA.

FORMING-MACHINE.

1,019,073.

Specification of Letters Patent.

Patented Mar. 5, 1912.

Application filed August 4, 1909. Serial No. 511,094.

To all whom it may concern:

Be it known that I, JOHN NAZEL, a citizen of the United States, residing at Philadelphia, in the county of Philadelphia and 5 State of Pennsylvania, have invented certain Improvements in Forming-Machines, of which the following is a specification.

This invention is a forming machine adapted for shaping bars and like articles. 10 Its leading objects are to provide improved means whereby shapes having various curvatures can be produced by simple adjustments and operations, with the least practicable expenditure of power.

15 In the preferred construction, a revoluble form is combined with a bed or anvil having separately movable elements adjusted and supported by the form and a reciprocating head or ram having several elements 20 adjustable to the form of the bed or anvil and coöperating therewith for the production of the desired shape.

In the drawings, Figure 1 is a front elevation of a machine embodying my improvements with a part broken away to show the interior construction; Fig. 2 is a sectional elevation taken on the line 2—2 of Fig. 1; Fig. 3 is a sectional elevation taken on the line 3—3 of Fig. 1; and Fig. 4 is a 30 sectional elevation taken on the line 4—4 of Fig. 1.

The machine represented in the drawings comprises the housings 1 having journaled therein the shaft 2 on which is fixed the 35 form 3 comprising sets of graduated cams 3^a, 3^b and 3^c, the general contour produced by these cams being a surface of revolution formed by revolving a curve of gradually varying diameter. That is to say, the form 40 is a cam tapering from its median portion toward its ends, whose transverse sections are spirals and whose contour lines lying in planes passing through its axis of revolution gradually vary from the curve 3^b—3^c—3^b 45 of short radius to the curve 3^c—3^b—3^c of larger radius. The shaft 2, with the form 3 thereon, is revolved and held with the desired curve uppermost by a worm wheel 4 fixed on a shaft end and in engagement with this wheel a worm 5 on a revolving shaft 6.

A bed plate or table 7 is supported by and extends between the housings 1 above the form 3. Connected with the part 7 is a 55 bed or anvil 8 comprising the elements 8^a

which are separately movable in the way 7^a of the table. The elements 8^a are provided with the enlarged tabs 8^b which limit their downward movements and coact to provide the variable bearing surface or head 60 of the anvil, this surface or contour being similar to the contour of the form 3 upon which the elements 8^a rest.

A head or ram is formed by a cross beam 9, having end bearings 9^a, which move in 65 vertical ways 1^a of the housings, and the elements 10 movable vertically in the way 9^b of the beam, the elements having the enlargements 10^a and 10^b at their opposite ends for limiting their vertical movements, 70 and in the case of the parts 10^b for providing the desired bearing surface. The bearings 9^a are movable relatively to the beam 9 and have the rods 9^c passing therethrough for drawing them up and clamping the 75 members 10 in their desired position, which is obtained by dropping them when loose upon the properly arranged members 8. These rods 9^c are suitably provided with heads 9^d 80 for engaging one of the bearings and with the screw threaded ends 9^e for engaging the pinions 9^f, which are revolved to loosen and tighten the rods by means of a pinion 9^g journaled upon one of the bearings. The cross beam is provided with the journals 9^h 85 which are engaged by rods 11 journaled upon the cranks 12^a and 12^b of a crank shaft 12, the latter being journaled in the bearings 1^b and driven in any suitable manner, 90 as by a pulley 12^c.

In the operation of the machine, when the form 3 has been revolved by the worm 5 and wheel 4 to the position required for giving the bed or anvil 8 the configuration desired in the bar or other article to be 95 shaped, the head is lowered and the elements 10, being loose in the cross beam, are adjusted so that their lower ends take the form of the bed's contour, in which position they are clamped by drawing up the 100 rods 9^c. The mechanism being adjusted, the head is reciprocated by revolving the driving pulley and articles placed in succession upon the anvil 8 are pressed to form by the action of the elements thereon. 105

Having described my invention, I claim:

1. In a machine of the character described, a master form revoluble for adjustment and means for retaining it in adjusted position, in combination with mechanism comprising 110

- a plurality of elements which are relatively adjustable by said master form and adapted for bending articles to shapes determined by the setting of the master form.
5. 2. In a machine of the character described, a master form revoluble for adjustment and means for retaining it in adjusted position, in combination with reciprocating elements adjusted relatively by said master form and thereby adapted for bending articles to shapes determined by the setting of the master form.
10. 3. In a machine of the character described, a revoluble form, a set of longitudinally movable elements adjusted and supported by said form, a second set of longitudinally movable elements adjustable to conform with the positions of said elements first named, and means for reciprocating said second set of elements.
15. 4. In a machine of the character described, a revoluble form having longitudinal contour curves of various diameters, in combination with a bed comprising separately movable elements adjusted and supported by said form, and a reciprocating head having separately movable elements adapted to coact with said elements first named.
20. 5. In a machine of the character described, a revoluble form having gradually varying spiral cross sectional contour curves, in combination with guiding means, and separately movable elements controlled by said

guiding means and relatively adjusted by means of said form.

6. In a machine of the character described, a housing, a form journaled therein, guiding means supported by said housing, and separately movable elements controlled by said guiding means and adjusted relatively by 40 said form.

7. In a machine of the character described, housing mechanism, a form journaled in said mechanism, guiding and supporting means fixed to said mechanism, elements held by and movable vertically in said means by said form, a reciprocating member guided by said mechanism, and elements held by and movable vertically in said member. 45

8. In a machine of the character described, a housing, a form journaled in said housing a bed piece fixed to said housing, elements separately movable in said bed piece by said form, a reciprocating head piece guided by 55 said housing, and elements separately movable in said head piece by said elements first named.

In witness whereof I have hereunto set my hand this 3rd day of August, 1909, in 60 the presence of the subscribing witnesses.

JOHN NAZEL.
